CLAIM

The ornamental design for a package for a toner cartridge, as shown and described.

DESCRIPTION

FIG. 1 is a front elevation of a package for a toner cartridge according to the present invention;

FIG. 2 is a rear elevation thereof;

FIG. 3 is a top plan view thereof;

FIG. 4 is a bottom plan view thereof;

FIG. 5 is a right side elevation thereof; and,

FIG. 6 is a top, front and right side perspective view thereof.

The broken lines in FIGS. 1-6 represent fold lines.
